UNITED STATES PATENT OFFICE

JAMES R. ADAMS, OF ATLANTA, GEORGIA

SCAFFOLD SUPPORT

Application filed March 13, 1931. Serial No. 522,362.

This invention relates to a scaffold support and has for one of its important objects to provide, in a manner as hereinafter set forth, a scaffold support which is particularly for use by brick layers on the outside of a building wall which is under construction, the device embodying hoisting means for raising or lowering the scaffold as desired, said hoisting means being arranged in a novel manner so as to be out of the way of the mechanics who are constructing the walls.

Other objects of the invention are to provide a scaffold support of the character described which will be simple in construction, strong, durable, compact, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in rear elevation showing a pair of scaffold supports constructed in accordance with this invention mounted in operative position with the boards or platforms mounted thereon.

Figure 2 is a view in side elevation of the scaffold support.

Figure 3 is a view in top plan thereof.

Figure 4 is a view in vertical section taken substantially on the line 4-4 of Figure 3.

Figure 5 is a view in vertical cross section taken substantially on the line 5-5 of Figure 4.

Figure 6 is a detail view on an enlarged scale through the hoisting mechanism and taken substantially on the line 6-6 of Figure 2.

Figure 7 is a detail view principally in section showing the means for adjustably mounting the wall engaging roller on the frame of the scaffold support.

Figure 8 is a detail view showing the gear which drives the drums.

Figure 9 is a view in top plan showing the adjacent end portions of a pair of platforms

which are connected together and disposed for rest on the supports.

Figure 10 is a view in side elevation and on an enlarged scale of the connected ends of the platforms illustrated in Figure 9.

Referring to the drawings in detail, it will be seen that the reference numeral 1 designates generally the frame of the scaffold support constituting this invention and said frame comprises a substantially U-shaped front member 2, the free ends of the leg portions of which are secured rigidly to the opposite sides or legs of a horizontally disposed substantially U-shaped member 3, the front member 2 being connected to the horizontal member 3 adjacent the bight portion of said member 3.

The free end portions of the legs of the horizontal member 3 are rigidly connected to intermediate portions of the legs of a substantially inverted U-shaped member 4.

The frame 1 of the scaffold support further includes an upper substantially U-shaped horizontal member 5 which is reversely disposed with respect to the lower horizontal member 3 and which has the free end portions of its legs rigidly connected to the sides of the substantially inverted U-shaped vertical member 4 adjacent the top or bight portion of said member 4.

A pair of braces or struts 6 are disposed at an inclination and have their lower end portions rigidly secured in any suitable manner to the lower end portion of the member 2 on the opposite sides thereof and said braces or struts have

their upper end portions rigidly secured in any suitable manner to the upper horizontal member 5 on the opposite sides and adjacent the bight portion thereof. Intermediate portions of the braces or struts 6 are rigidly secured in any suitable manner to the free end portions of the legs of the lower horizontal member 3 and to intermediate portions of the legs of the substantially inverted U-shaped vertical member 4.

A forked bracket 7 is provided with rows of openings (see Figure 7) in a horizontal plane to the front vertical member 2, said bracket being connected to the bight or lower end portion of the member 2. The openings

95

100

- referred to are designated by the reference numeral 8 and are for the reception of a securing bolt 9 which also passes through the bight portion of the front vertical member 2.
- 5 A roller 10 is journaled on the free end of the bracket 7 for rolling contact with the wall under construction in a manner to maintain the scaffold in spaced relation thereto and to facilitate raising or lowering the scaffold.
- 10 Horizontal rods 11 and 12 extend between the upper and lower portions of the bars 6 and have rotatably and slidably mounted thereon the grooved pulleys 13 and 14, respectively.
- 15 Vertically spaced upper and lower shafts 15 and 16, respectively, extend between the legs or side portions of the member 4 of the frame 1 and have journaled for rotation thereon the drums 17 and 18, respectively.
- 20 One of the heads or end flanges on each of the drums 17 and 18 is peripherally toothed in a manner to provide the gears 19 while the other heads or end flanges of the drums are provided with the ratchet teeth 21 for engagement by the dogs 21' which are pivotally mounted on one of the legs or side portions of the member 4 of the frame 1 for releasably locking the drums against rotation in one direction.
- 25 A ratchet wheel 22 is provided with a hub portion 23 one end portion of which is journaled for rotation in the leg or side portion of the member 4 of the frame 1 which is adjacent the gears 19, suitable means such as a retaining collar 24 being secured on the inner end of said hub 23 for retaining the ratchet wheel 22 in position. A shaft 25 is splined in the hub 23 of the ratchet wheel 22 and said shaft is disposed between the drums 17 and 18. One end portion of the shaft is rotatably and slidably supported in the leg or side of the member 4 of the frame 1 upon which the dogs 21 are mounted. Heads 26 are fixed on the ends of the shaft 25 for limiting the sliding movement of said shaft in opposite directions. A gear 27 is fixed on an intermediate portion of the shaft 25 between the legs or side portions of the member 4 of the frame 1 and said gear is adapted to be engaged with the gears 19 of the upper and lower drums 17 and 18 in a manner to connect said drums to the shaft 25 for actuation thereby. The drums 17 and 18 will, of course, be rotated in the same direction by the gear 27.
- 30 A lever 28 is mounted for oscillation on the outer portion of the hub 23 of the ratchet wheel 22 and said lever has pivotally mounted thereon a pawl 29 which is engageable with the ratchet wheel 22 in a manner to operatively connect said ratchet wheel to the lever 28 for actuation in one direction by said lever.
- 35 As best seen in Figures 9 and 10 of the drawings, the platforms which are designated by the reference numeral 30 comprise a

plurality of boards 31 which are connected together at their ends by the transverse cleats 32. Suitable coupling devices 33 tie or connect the platforms 30 together at their ends.

Cables 34 and 35 pass under the pulleys 13 and 14, respectively, and are reversely wound on the drums 17 and 18, as clearly seen in Figure 4 of the drawings.

In use, the dogs 21' normally retain the drums 17 and 18 against rotation in a direction to permit the cables 34 and 35 to unwind therefrom. When it is desired to raise the scaffold the lever 28 is oscillated in a manner to rotate the shaft 25 through the medium of the ratchet wheel 22 and the pawl 29, it being understood, of course, that the gear 27 is in mesh with the gears 19 of the drums. It will thus be seen that the drums 17 and 18 will be simultaneously actuated in the same direction. When it is desired to lower the scaffold, the dogs 21' are, of course, kicked or lifted out of engagement with the ratchet teeth 21 of the drums 17 and 18 to permit rotation of said drums in a direction to unwind the cables 34 and 35 therefrom.

When it is desired to unwind the cables one at a time instead of simultaneously, thereby rendering it necessary to retain one of the drums against rotation while the other of said drums is released, the shaft 25 is shifted longitudinally to the position indicated in broken lines in Figure 6 of the drawings for disengaging the gear 27 from the gears 19 of the drums, thus disconnecting said drums from each other. Then, as will be obvious, the dog 21' is disengaged from the drum which is desired to be released and the cable is unwound therefrom. The necessity for unwinding the cables 34 and 35 one at a time arises when the supporting beams from which said cables are suspended are to be moved upwardly as the erection of the building or other structure progresses.

As may be apparent, the mechanics work on the platform or boards which are disposed on the lower horizontal members 3 of the frame 1 and the material is placed on the platform or boards which are supported on the upper horizontal member 5 of the frame. The mounting of the winding mechanism on the rear vertical member 4 of the frame 1 disposes said mechanism in a position where the same will not be in the way of the mechanics working on the wall which is disposed in front of the scaffold. This constitutes a most important and desirable feature of the invention. It will further be apparent that the winding mechanism is mounted for operation on an intermediate portion of the supporting frame 1 and this is another important feature of the invention.

It is believed that the many advantages of a scaffold support constructed in accord-

ance with the present invention will be readily understood, and although the preferred embodiment of the invention is as illustrated and described, it is to be understood that changes in the details of construction and in the arrangement of parts may be resorted to without departing from the spirit of the invention or from the scope of the appended claims.

10 What is claimed is:—

1. A scaffold support of the character described comprising a frame including upper and lower substantially horizontal portions for supporting material and workmen's platforms, respectively, drums mounted for rotation on an intermediate portion of the frame, pulleys mounted for rotation adjacent the ends of the frame, supporting cables trained under the pulleys and connected to the drums for winding on said drums, and means for simultaneously actuating the drums in the same direction relative to each other, said means comprising a shaft journaled in the frame, a gear mounted on the shaft for rotation therewith, gears on the drums engaged with the first named gear for actuation thereby, a ratchet wheel keyed to the shaft, a lever mounted for oscillation, and a pawl pivotally mounted on the lever and operatively engageable with the ratchet wheel for actuating said ratchet wheel in one direction upon oscillation of the lever.

2. A scaffold support of the character described comprising a frame including a vertically disposed, substantially U-shaped member, a substantially U-shaped lower horizontal member connected to the free end portions of the legs of the substantially U-shaped vertical member, the legs of this substantially U-shaped vertical member being connected to the legs of the lower horizontal member adjacent the bight portion thereof, a substantially inverted U-shaped vertical member having its legs rigidly connected to the free end portions of the legs of the lower horizontal member at intermediate points, an upper substantially U-shaped horizontal member having the free end portions of its legs rigidly connected to the legs of the substantially inverted U-shaped vertical member adjacent the bight portion thereof, the upper and lower horizontal members being adapted to support material and workmen's platforms, respectively, a pair of inclined bars having their end portions rigidly secured to the bight portions of the first named vertical member and to the second named horizontal member of the frame, said bars having their intermediate portions rigidly secured to the free end portions of the legs of the first named horizontal member and to intermediate portions of the legs of the second named vertical member.

3. A scaffold support of the character described comprising a frame including a

vertically disposed, substantially U-shaped member, a substantially U-shaped lower horizontal member connected to the free end portions of the legs of the substantially U-shaped vertical member, the legs of this substantially U-shaped vertical member being connected to the legs of the lower horizontal member adjacent the bight portion thereof, a substantially inverted U-shaped vertical member having its legs rigidly connected to the free end portions of the legs of the lower horizontal member at intermediate points, an upper substantially U-shaped horizontal member having the free end portions of its legs rigidly connected to the legs of the substantially inverted U-shaped vertical member adjacent the bight portion thereof, the upper and lower horizontal members being adapted to support material and workmen's platforms, respectively, a pair of inclined bars having their end portions rigidly secured to the bight portions of the first named vertical member and to the second named horizontal member of the frame, said bars having their intermediate portions rigidly secured to the free end portions of the legs of the first named horizontal member and to intermediate portions of the legs of the second vertical member, and means for raising or lowering the frame, said means comprising vertically spaced drums mounted for rotation in the second named vertical member, means for simultaneously actuating the drums, and cables for supporting the frame in suspended position connected to the drums for winding thereon.

4. A scaffold support of the character described comprising a frame including a vertically disposed, substantially U-shaped member, a substantially U-shaped lower horizontal member connected to the free end portions of the legs of the substantially U-shaped vertical member, the legs of this substantially U-shaped vertical member being connected to the legs of the lower horizontal member adjacent the bight portion thereof, a substantially inverted U-shaped vertical member having its legs rigidly connected to the free end portions of the legs of the lower horizontal member at intermediate points, an upper substantially U-shaped horizontal member having the free end portions of its legs rigidly connected to the legs of the substantially inverted U-shaped vertical member adjacent the bight portion thereof, the upper and lower horizontal members being adapted to support material and workmen's platforms, respectively, a pair of inclined bars having their end portions rigidly secured to the bight portions of the first named vertical member and to the second named horizontal member of the frame, said bars having their intermediate portions rigidly secured to the free end portions of the legs of the first named horizontal member and to intermediate portions of the legs of the second named vertical member.

- tions of the legs of the second named vertical member, and means for raising or lowering the frame, said means comprising vertically spaced drums mounted for rotation in the second named vertical member, means for simultaneously actuating the drums, and cables for supporting the frame in suspended position connected to the drums for winding thereon, the first named means further including horizontal rods extending between the inclined bars of the frame adjacent the upper and lower ends thereof, and peripherally grooved pulleys rotatably and slidably mounted on the rods, the cables being trained under said pulleys.
5. A scaffold support of the character described comprising an upper horizontal member, a vertical member rigidly connected to one end portion of the upper horizontal member and depending therefrom, a lower horizontal member rigidly connected to the vertical member and extending laterally therefrom, said upper and lower horizontal members being adapted to support material and workmen's platforms, respectively, another vertical member rigidly connected to one end portion of the lower horizontal member and suspending therefrom in spaced relation from the first named vertical member, inclined bars having their end portions rigidly connected to one end portion of the upper horizontal member and to one end portion of the second named vertical member, intermediate portions of the inclined bars being rigidly connected to the lower horizontal member and the first named vertical member.

In testimony whereof I affix my signature.
JAMES R. ADAMS.
